MACHINE FOR THE PRODUCTION OF KNITTED FABRICS

Application filed January 8, 1930, Serial No. 418,229, and in Great Britain March 28, 1929.

This invention comprises improvements in machines for the production of knitted fabrics and has for its object to provide means for producing a knitted fabric wherein the tendency to rove or ladder is eliminated or minimized.

According to the present invention a machine for producing knitted fabric is provided embodying a needle having a plurality of displaceable latches located one below another on its stem, thread feeding means, means for effecting relative movement between said needle and thread feed for stitch production, and said relative movement being such as to cause thread fed to the needle to be looped through and also around or over another loop on said needle.

The passing of a thread loop through and around another loop by means of a plural latch needle as above results in one loop being tied or locked upon another, and the production of a tied or locked loop or number of loops in this manner in a knitted fabric effectively prevents or minimizes the tendency to unravel or ladder.

In this arrangement the plural latch needle or needles employed in the machine are provided with two latches spaced one below the other, and in such arrangement said needles when operating to produce a tied stitch are first raised to a position wherein the existing loop thereon is cleared below the bottom latch and new thread is fed between the two latches, after which the needle is lowered so as to cause the existing loop to be drawn into the needle hook and the newly fed loop to be drawn through said existing loop and pass over or around same.

The plural latch needle or each of said needles may, however, be provided with three or more pivoted latches spaced one below the other, and when a locked or tied stitch is produced on such needle, the needle operating cam functions to raise same to a position wherein the existing loop passes below the lowermost latch, and such existing loop and a loop formed from new thread are caused to pass one through the other a plurality of times.

For the purpose of more fully describing

the nature of this invention reference will now be made to the accompanying drawings, wherein:—

Figure 1 illustrates a suitable arrangement of knitting cams with coacting double latch needles and associated thread feed employed in the present invention for producing a tied stitch.

Figure 2 illustrates the several successive steps in the production of a simple form of tied stitch employing a two latch needle.

Figure 3 illustrates steps in the production of a tied stitch with a three latch needle.

Figure 4 is an enlarged side-elevational view of a two latch needle as employed in this invention.

Figure 5 is a front elevation of the needle shown in Figure 4.

In one method of carrying out the invention a knitting machine is provided wherein a needle *a* or each of a predetermined number of said needles carries two pivoted latches *b*, *c*, on the same side of the shank, said latches being located one above the other and so spaced that the lower latch *c* when raised abuts against the end of the upper latch *b* when the latter is in the lowered position, said upper latch *b* when raised being adapted to abut against and close the hook *d* in the usual manner.

The manner in which the plural latch needle functions necessarily depends upon the type of stitch or fabric to be produced but the invention will first be described as employing a two latch needle as shown in Figure 2. In this arrangement the cam operates upon the needle to elevate same to such a height that the old loop *e* is drawn down over both latches *b* and *c* and becomes positioned beneath the lower latch, said latches being in a lowered position as shown at the third needle from the left in Fig. 2. New thread *f* is then laid on the shank of the needle between the two latches and on the downward movement of the needle the lower latch *c* is raised by the old loop *e* and the end of said latch abuts against or overlaps the extremity of the depending upper latch *b*, said old loop rising over the two abutting latches and over the newly laid thread loop *f* into the hook *d*.

of the needle *a*, the new loop *f* being thus drawn through the old loop *e* as shown at the fourth needle in Fig. 2. The further downward movement of the needle causes the new loop *f* to raise the upper latch *b* and be cast off the needle, thus the old loop is drawn through the new loop and the old loop is retained in the hook of the needle in readiness for the production of the next stitch on said needle as shown at the fifth needle in Fig. 2. In this way it will be seen that a loop of thread is passed both through and around another loop and becomes tied thereon when the usual tension is applied to the thread.

15 A suitable cam for producing a tied or locked stitch as above is illustrated in Figure 1, the butt of the needle on which a locked stitch is to be formed being caused to travel up the two cam pieces 1, 2, to the position marked 3 at which the old loop *e* is cleared beneath the lower latch, the needle then traveling down beneath cam 4 and taking the newly fed thread *f* from a feeder 6 the before-described intermeshing of the loops *e* and *f* being effected during the downward movement of the needle along said cam 4.

In order to obviate the possibility of the lower latch *c* being retained in a raised position during the upward movement of the needle for clearing the old loop *e* and thus preventing the laying of the new thread *f* between the two latches, means are advantageously provided for positively lowering said lower latch *c* during such movement.

30 35 In one simple method of accomplishing this a small auxiliary cam 5 is advantageously provided at a position substantially half-way up the rise of the needle to the clearing position intermediate the two cam pieces 1 and 2, said auxiliary cam 5 being so designed that when the needle has risen to a position in which the old loop *e* has passed beneath the extremity of the downturned upper latch *b*, see first needle from the left in Fig. 2, said

40 45 needle is given a short downward movement to an extent sufficient to cause the old loop *e* to rise upwardly beneath the upper latch *b* and come into position on the inner side of the upturned lower latch *c*, the continued upward movement of the needle along the cam piece 2 then causing the said old loop *e* positively to draw down the lower latch *c* so as to leave the two latches open for permitting the laying of the new thread.

50 55 It will be appreciated that in order to accommodate the thread *f* which is fed between the latches *b*, *c*, a clearance is required between the needle shank *a* and the back of the top latch *b*, and this effect may be accomplished by extending the spoon portion *b*¹ of said latch *b* towards the latch rivet somewhat further than is customary and bending or setting back the tip of said lengthened spoon *b*¹ so as to prevent same projecting too far from the shank.

Alternatively, the necessary clearance may be produced by so determining the length of the saw cut in the needle shank as to prevent the latch lying back close on to said shank when opened.

70 Advantageously the total lateral width at the point where the closed lower latch *c* overlaps the open top latch *b* does not exceed that at the hook *d* of the needle when the top latch is closed.

75 Further, the lower latch *c* is provided with a spoon portion *c*¹ instead of the usual bulb end, and said spoon portion is preferably somewhat wider than that of the top latch and is well cupped so as to fit snugly over the tip of said top latch.

80 In Figure 3 is shown a needle having three latches, the middle latch *g* and lowermost latch *h* being each adapted when in their fully raised position to abut against and slightly overlap the latches disposed next above same.

The function of the needle is in this case similar to that before described, the needle being elevated to such position that the old loop *e* passes beyond the lowermost latch *h* 90 and new thread *f* is laid on the shank of the needle between the middle and lower latches *g*, *h*.

95 On the first part of the downward movement of the needle the lowermost latch *h* is reversed to abut against the middle latch *g* and the old loop *e* guided over the abutting latches and the newly laid thread *f* covered thereby, and passing toward the shank of the needle between the upper and middle latches 100 *i* and *g*. On further downward movement of the needle the middle latch *g* is reversed by the newly laid thread loop *f* and abuts against the uppermost latch *i*. The newly laid loop is thereby guided over the abutting latches 105 *h*, *i* covering the old loop *e* and passes toward the hook of the needle; the old thread loop *e* subsequently reverses the uppermost latch *i* and is thereby cast off the needle.

110 Compared with the stitch produced by a two latch needle the result obtained is that the newly formed thread loop *f* is once more drawn through the old loop *e* to produce a double intertwining effect.

115 In the three latch needle sufficient clearance is provided at the rear of the middle latch *g* when open for accommodating the thread *f* laid between the two latches *g*, *h*.

120 A cam system for producing this doubly tied stitch would conveniently embody two small auxiliary cams such as 5 (Figure 1) suitably spaced so as to ensure the two latches *g*, *h* being lowered during the rising of the needle to the clearing position.

125 If desired the hook of the plural latch needle may be of spring formation substantially similar to the hook of a bearded needle so as to facilitate the casting off of loops. In this connection it will be seen that with an ordinary rigid hook, strain may be thrown 130

on the loop being cast off which strain might possibly result in breakage of the loop. If, however, the hook has a spring action same will yield and allow the loop to pass easily off the needle.

5 I claim:

1. In a machine for producing knitted fabrics a needle having a plurality of displaceable latches located one below another on its stem, thread feeding means, means for effecting relative movement between said needle and thread feed for stitch production, and said relative movement being such as to cause thread fed to the needle to be looped through and also around or over another loop on said needle.

10 2. In a machine for producing knitted fabrics a knitting needle having two pivoted latches spaced one below another on the needle stem, thread feeding means, cam means functioning to reciprocate said needle, said cam means operating the needle so as first to clear an existing loop thereon beneath the lowermost latch and permit of fresh thread 15 being fed to said needle between its latches and subsequently to pass a loop of said fresh thread through and also around or over the said existing loop.

20 3. In a machine for producing knitted fabrics a needle having three pivoted latches spaced one below the other on the needle shank, a thread feed to said needle, means operating on the needle to elevate the same to a position wherein an old loop thereon passes 25 below the lowermost latch and new thread is laid on the needle shank between the middle and lower latches said needle operating means functioning subsequently to lower the needle so as to cause a loop of the newly laid thread 30 first to be drawn through the old loop then passed over or around said loop and subsequently drawn a second time through said old loop so as to produce a double intertwining effect of one loop upon the other.

35 4. In a machine for producing knitted fabrics, a needle having a plurality of pivoted latches spaced one below the other on the needle stem, the extremity of said latches being adapted to abut or overlap when extending in opposite directions, thread feeding means to said needle, a cam device functioning to displace the needle to a position wherein thread is fed between the latches thereon and subsequently to cause a loop of 40 newly fed thread to pass through and also around an existing loop on said needle, and an auxiliary cam associated with said needle operating cam device functioning positively to move the latches apart for permitting the 45 feeding of new thread between same.

50 ROBERT KIRKLAND MILLS.
